US00D360388S

United States Patent [19]

Weder et al.

[11] **Patent Number: Des. 360,388**[45] **Date of Patent: ** Jul. 18, 1995****[54] FLOWER POT COVER**

[75] Inventors: **Donald E. Weder; Joseph G. Straeter,**
both of Highland, Ill.

[73] Assignee: **Highland Supply Corporation,**
Highland, Ill.

[*] Notice: The portion of the term of this patent
subsequent to Oct. 11, 2002 has been
disclaimed.

[**] Term: **14 Years**

[21] Appl. No.: **808,547**

[22] Filed: **Dec. 16, 1991**

Related U.S. Application Data

[63] Continuation-in-part of Ser. No. 710,272, Jun. 4, 1991,
which is a continuation-in-part of Ser. No. 617,454,
Nov. 21, 1990, abandoned, and a continuation-in-part
of Ser. No. 411,249, Sep. 22, 1989, and Ser. No.
411,247, Sep. 22, 1989, and Ser. No. 411,245, Sep. 22,
1989.

[57] CLAIM

The ornamental design for a flower pot cover, as shown
and described.

DESCRIPTION

FIG. 1 is a reduced top plan view of our new flower pot
cover design;
 FIG. 2 is a reduced side elevational view of the front
side thereof;
 FIG. 3 is a reduced side elevational view of the back
side thereof;
 FIG. 4 is a reduced side elevational view of the left side
thereof;
 FIG. 5 is a reduced side elevational view of the right
side thereof;
 FIG. 6 is a reduced bottom plan view thereof;
 FIG. 7 is a reduced side elevational view of the design
of FIG. 1, the only difference being the angle of the
skirt; and,
 FIG. 8 is a reduced side elevational view of the design
of FIG. 1, the only difference being the angle of the
skirt.

The flower pot cover has no substantial thickness.
